UNITED STATES PATENT OFFICE.

JOHN W. NESMITH, DECEASED, LATE OF DENVER, COLORADO, BY HARPER M. ORAHOOD, EXECUTOR, OF DENVER, COLORADO, ASSIGNOR TO COLORADO IRON WORKS COMPANY, OF DENVER, COLORADO, A CORPORATION OF MAINE.

APPARATUS FOR SMELTING ORES.

995,365.

Specification of Letters Patent. Patented June 13, 1911.

Application filed October 26, 1910. Serial No. 589,273.

To all whom it may concern:

Be it known that JOHN W. NESMITH, deceased, late a citizen of the United States, and resident of Denver, Colorado, did invent certain new and useful Improvements in Apparatus for Smelting Ores, of which the following is a specification.

This invention relates to a method of smelting ores in what is designated a hydro-
carbon blast furnace having one or more
10 external or auxiliary combustion chambers
permanently or removably attached thereto
and made a part thereof, wherein hydrocarbon
or other fluid or pulverized solid fuel is
15 burned for the production of smelting heat,
and this heat is projected or introduced by
convection into the blast furnace and into
contact with the ores charged therein.

In the accompanying drawings, Figure 1
20 is a vertical section through a form of fur-
nace adapted to carry out the process of
the invention. Fig. 2 is a plan view partly
in section of a modification, and Fig. 3 is an
elevation partly in section of the same.

25 In these figures an ordinary furnace stack
is shown at A provided with a bustle pipe
K, and an air supply pipe G. While it is
preferred to use in carrying out the invention
30 a vertical stack of the general type
shown, the invention is not limited in this
connection.

It will be observed that the combustion
chamber indicated at C is relatively large,
35 and this has been found to be necessary for
the successful carrying out of the process in-
volved. The best results are secured by the
use of a chamber having a volume of space
not less than 35 cubic feet for each pound
40 of combustible burned per minute. Ore is
charged into the top of the stack and the
base of the column fills the opening D lead-
ing to the combustion chamber, the ore tak-
ing the natural slope of such loose material,
45 usually of about 45°, or as shown approxi-
mately by the dotted line x—y. Combustion
sufficiently intense for the purpose of
smelting ores is maintained in the combus-
tion chamber C, the heated gases passing out
50 through the ore body which they enter along
the surface of the slope and thence to es-
cape through the blast furnace stack A,
heating the body of ore first along the sur-

face of its slope x—y, where it begins first to
fuse or melt, and, as it softens its natural
slope becomes flatter toward its lower end, 55
or, say 30 degrees, as represented by the
curved line x—y', and when fully molten or
fluid at the lower extreme, will seek a level
on the hearth of the combustion chamber C
in any space not occupied by the solid or 60
semi-molten material, and may be tapped off
from the combustion chamber C at F. In
the meantime, fresh ore partly fused is con-
stantly entering from the stack A, and so
maintains a slope of some surface outline, on 65
which the heat of combustion radiates and
through which the heated gases pass on and
out through the ore.

It will be observed that the twyters B are
located below the line of the top of the com-
bustion chamber C for the reason that it has
been found in practice that when located
above the arch forming the passage D a
smelting zone is formed secondary to that
70 maintained through the heated products of
combustion at the entrance D to the com-
bustion chamber, the result being to lique-
75 ate the more fusible constituents which flow
away and leave a skeleton hanging in the
shaft thus obstructing or terminating the
smelting operation. By locating the twyters
near the hearth where the smelting takes
80 place the oxidation blast may be added at a
point where it does not interfere with the
smelting action. This is rendered possible
85 of course, by the fact that the fuel is burned
in the combustion chamber apart from the
ore.

In order to prevent the burning out of the
arch at the point where the ore begins to 90
slope and enter the combustion chamber a
water pipe I is located at this point. If
found desirable, the combustion chamber
may be water jacketed.

The blast furnace stack A is not abso-
lutely necessary for the application of this
method to the smelting of some kinds of
ores. Some other kind of appliance of
suitable proportion for charging the ores
into and properly connecting with the com-
bustion chamber C would answer such pur-
pose, but having twyters near the hearth
100 through which an air blast may be blown
adapts the blast furnace to preparing cer-

tain ores, such as heavy sulfids for this method, by oxidizing or burning off a part of their sulfur content, and hence to the blast furnace construction is given the preference for the application of this method.

It has been found in practice in the smelting of ores of gold, silver, lead and copper, by the hydrocarbon system, where the heat generated in the combustion chamber is caused to pass into the blast furnace, and in direct contact with the body of ore, that masses of ore become semifused, but not sufficiently fused or fluid to tap off as slag and matte—that is to say, not sufficiently fluid or molten thin enough whereby they properly separate. To overcome this difficulty prior to tapping, and to prevent the clogging of the taps, the method has been adopted as described of allowing the ore, in a semifused or thickly molten condition, to run or flow into the opening D formed by the junction of the combustion chamber with the blast furnace to present there a sloping surface whereby the semifused ore is exposed to the direct heat generated within the combustion chamber, and is thereby caused to flow downwardly in the combustion chamber, being constantly exposed to the heat generated therein. The surface continuously melts off to thinner and thinner consistency as it becomes sufficiently heated, and in the finally smelted and fluid condition necessary or desirable finds its level on the hearth of the combustion chamber, thence to be tapped off. It has been found, however, in practice that it is absolutely necessary to tap the fused product at a point which must be removed a considerable distance from the base of the slope of the ore column, as otherwise the tap will inevitably be clogged and to this end it will be observed that an elongated combustion chamber is used and the tap for the slag and matte is removed from the entrance D a distance which will absolutely preclude any clogging or choking of the outlet by the viscous or semi-fluid mass.

Fig. 2 is a plan and elevation, partly in section, showing a furnace having a plurality of combustion chambers, and illustrating how, in a furnace adapted to carry out this

method, the combustion chambers may be made removable.

The reference letters designate corresponding parts in both drawings. 55

L represents an oil or other burner of any suitable construction, e being the controlling valve.

H represents the inlet of the main blast which passes through the passage above the 60 combustion chamber and through the inlet shown in the front of the combustion chamber.

What is claimed is:

1. A furnace comprising a stack, a combustion chamber extending horizontally from the base of the stack and in communication therewith, means for supplying a blast to the stack, means for supplying fuel to said combustion chamber under pressure 70 and a tap opening in the combustion chamber removed from the position of the base or slope of the ore column, substantially as described. 65

2. A furnace comprising a stack, an elongated combustion chamber extending horizontally from the base of the stack and in communication therewith, means for supplying a blast to the stack, means for supplying fuel to said combustion chamber and 80 a tap opening in the combustion chamber in or near the end removed from the position of the base or slope of the ore column, substantially as described. 75

3. A furnace comprising a stack, a combustion chamber extending horizontally from the base of the stack and in communication therewith, means for supplying a blast to the stack, means for supplying fuel to said combustion chamber, twyers supplemental to the main blast for supplying air to the base of the ore column in the stack near the hearth, and a tap opening in the combustion chamber removed from the position of the base or slope of the ore column, 90 substantially as described. 85
